Primary Examiner — Rhea Shields(74) *Attorney, Agent, or Firm* — Chang & Hale LLP(57) **CLAIM**

The ornamental design for an instrument cart, as shown and described.

DESCRIPTION

FIG. 1 is a top, front, left perspective view of an instrument cart;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

In the drawings, the evenly spaced broken lines are for the purpose of illustrating portions of the instrument cart that form no part of the claimed design. The dash-dot broken lines are for the purpose of showing the boundaries of the claim that form no part of the claimed design.
